US00D950162S

(12) **United States Design Patent** (10) Patent No.: **US D950,162 S**
(45) Date of Patent: ** *Apr. 26, 2022

(54) **CLIP FOR A DOOR ASSEMBLY OF AN ANIMAL ENCLOSURE**

(71) Applicant: **Mid-West Metal Products Company, Inc.**, Muncie, IN (US)

(72) Inventors: **Brad Cantwell**, Muncie, IN (US); **Stew Kerr**, Muncie, IN (US); **Michael E. Greene**, Muncie, IN (US); **David J. Nolley**, Muncie, IN (US)

(73) Assignee: **MID-WEST METAL PRODUCTS COMPANY, INC.**, Muncie, IN (US)

(*) Notice: This patent is subject to a terminal disclaimer.

(**) Term: **15 Years**

(21) Appl. No.: **29/716,627**

(22) Filed: **Dec. 11, 2019**
